O. HABICHT

PRESSING BOW AND LAST

Filed June 28, 1922

FIG. 1.

FIG. 2.

Inventor
Otto Habicht,
By Henry B. H. atty.

UNITED STATES PATENT OFFICE.

OTTO HABICHT, OF MUHLHEIM-ON-THE-MAIN, GERMANY.

PRESSING BOW AND LAST.

Application filed June 28, 1922. Serial No. 571,427.

To all whom it may concern:

Be it known that I, OTTO HABICHT, a citizen of the German Republic, residing at Mühlheim-on-the-Main, Germany, have invented certain new and useful Improvements 5 in a Pressing Bow and Last, of which the following is a specification.

This invention relates to an improvement 10 of the device described in my prior Patent No. 1,445,942, dated February 20, 1923. According to this prior application the stud 15 designed to exert the pressure upon the front part of the last is guided in a sleeve located in the last; according to the present invention the arrangement is such that the use of the stud is not limited to a sleeve arranged at a determined point of the last but 20 that it can act upon different points. This permits the front stud on the bow to engage the last as far as possible toward the front 25 of the last as will be permitted by the upper closure of any style and size of shoe.

With this object in view the last has at its 30 front end a device which permits the stud to act at different points, the device consisting for instance of a rack, with the teeth of which the stud engages, said stud being conveniently shaped. Such an arrangement 35 permits, besides the advantage already mentioned, some other advantages. The rack serves to reinforce the last specially at the portion and it can be used further to receive, with lasts with exchangeable instep blocks, the front pin for fixing the block and eventually also the rear yielding pin although 40 as a rule the fixing of the front pin upon the rack would be sufficient. The fixation of this pin upon the rack instead of in the wooden part of the last presents the advantage that the pin can oppose a greater resistance to the strain than if it is fixed in the wood of the last, so that it does not get loose under the continuous strain.

In connection with lasts with exchangeable instep block the improved arrangement 45 presents further the advantage that the rack is completely covered by the wedge so that the last can be used also for other purposes.

In order that the invention may be clearly 50 understood, I shall proceed to describe the same with reference to the form of construction shown by way of example on the accompanying drawing, wherein:

Fig. 1 shows the last and pressure bow in 55 side elevation partly in section.

Fig. 2 is a side elevation of the last with exchangeable instep block thereon.

According to the invention a metal plate 2 is fixed by means of screws 3 at the front part of the last 1. Teeth 4 are arranged in 60 said metal plate 2 at convenient distances apart. The stud 6 bevelled at its lower end 5 and fixed in the presser bow 7 or in the part 9 of said presser bow inserted in the dove-tailed guide of the bow, is designed to 65 engage with any of the gaps between the teeth 4 of plate 2. The presser bow is removably fixed in the rear end of the last 1 by means of a second stud 10 guided in a sleeve 11. 70

The exchangeable wedge shaped part 12 of the last is fixed in a manner known per se in the main part of the last by means of stud 13 fixed upon the metal plate 2 and of a rear stud 14 which is pushed upward by 75 the action of a spring.

I claim:—

1. In combination with a presser bow for shoes, a last, a sleeve in the rear part of said last designed to receive a stud of the 80 presser bow, and means at the front part of the last designed to hold the second stud of the presser bow at different points.

2. In combination with a presser bow for shoes, a last, a sleeve in the rear part of 85 said last designed to receive a stud of the presser bow, and a rack at the front part of the last, the teeth of said rack being designed to be engaged by a second and pivotal stud on the presser bow. 90

3. In combination with a presser bow for shoes, a last, a sleeve in the rear part of said last designed to receive a stud of the 95 presser bow, and a toothed metal plate at the front part of the last, the teeth of said plate being designed to be engaged by a second and pivotal stud of the presser bow which is bevelled at its free end.

4. In combination with a presser bow for shoes, a last, a sleeve in the rear part of 100 said last designed to receive a stud of the presser bow, and a toothed metal plate at the front part of the last, the teeth of said plate being designed to be engaged by a second stud of the presser bow which is 105 bevelled at its free end and a slide adjustable on said bow carrying said second stud.

5. A last having a body portion and a removable instep block, a rack on the front part of said body portion, a stationary stud 110

on the front end of said rack and a spring projected stud at the rear of said rack, said studs inclined to one another and said instep block having holes to receive said studs, ⁵ the hole at the rear of said block for receiving said spring projected stud passing entirely through said block.

In testimony whereof I affix my signature in presence of two witnesses.

OTTO HABICHT.
